UNITED STATES PATENT OFFICE.

CHARLES O. ANDERSON, OF OMAHA, NEBRASKA.

RAILWAY-BRAKE-ADJUSTING MEANS.

Application filed January 30, 1925. Serial No. 5,787.

My invention relates to manually operated adjusting means for railway air-brakes. It is the object of my invention to provide simple and inexpensive means which may be readily applied to the present standard brake-rigging of railway cars, and which will enable accurate adjustment to be made of the slack or brake-shoe clearance when the brakes are in release position. A more particular object of my invention is to provide means for accurate adjustment of railway brake mechanism in which the adjusting mechanism is associated with the equalizing levers, or cylinder-lever and floating-lever, of the foundation brake-rigging, instead of being applied to the truck-levers. In brake mechanism of the latter class the adjustment of slack must be made separately for each truck of the car, while in brake-mechanism of the class to which my present invention is applied the adjustments are made at a single place for varying the slack of the brakes on both trucks of a car.

In the accompanying drawings Fig. 1 is a diagrammatic plan view of the brake-rigging of an ordinary freight-car, having my adjusting means applied to the floating-lever, or second equalizing-lever thereof, Fig. 2 is a similar view of a portion of the mechanism, drawn to a larger scale than in Fig. 1, Fig. 3 is a detail section on the line 3—3 of Fig. 2, Fig. 4 is a plan view showing portions of a brake mechanism having my adjusting means applied to the cylinder-lever or first equalizing-lever, Fig. 5 is a detail plan view of the adjusting means as applied to the cylinder-lever, and Fig. 6 is a detail side view of the adjusting-yoke on the piston-rod, the cylinder-lever being in section on the line 6—6 of Fig. 5.

Referring to Fig. 1, there is indicated in dotted outline the frame 7 of a freight-car, and the wheels 8 thereof, the brake mechanism being shown by full lines, in the usual relation to the car-body and wheels. The parts of the brake-mechanism indicated in the figure are the brake-shoes 9, brake-beams 10, dead-levers 11, live-levers 12, the bottom-rods 13 which connect the lower ends of the truck-levers, the brake-rods or top-rods 14 which connect the live-levers with the equalizing-levers, the latter being the floating-lever 15 and cylinder-lever 16, the connecting-rod 17 which connects the equalizing-levers to each other, the brake-cylinder 18, brake-piston-rod 19, hand-brake-rod 20, and

hand-wheel 21. It will be understood that all of the parts above named are constructed, proportioned and arranged to operate in the usual and well-known manner, the brake-cylinder being fixedly connected with and supported upon the sills of the car-frame, and the upper or fulcrumed ends of the dead-levers being pivotally connected with the truck-bolsters (not shown).

In the type of brake-rigging represented in Figs. 1, 2 and 3, adjustment of slack in the brake-mechanism is effected by varying the connection between the fulcrumed end of the floating-lever 15 and the fulcrum-bracket 22 which is fixedly secured to the sills of the car-frame. Said bracket 22 has a pair of spaced parallel plates between which the end of the lever extends, and said plates have therein a series of holes 23 for receiving the fulcrum-pin 24, said holes being uniformly spaced longitudinally of the bracket. In the ordinary construction the lever has a single hole for receiving the fulcrum-pin, so that the minimum amount of adjustment that may be effected is that resulting from transferring the fulcrum-pin from one of the holes 23 in the bracket to the next adjacent hole of the series. In my improved adjusting means I provide the lever 15 with laterally extending lugs 25 which form an enlargement or head in which are formed a plurality of holes 26 for receiving the fulcrum-pin 24. Said holes 26 are equidistant from the center of the pin 27 which connects the lever with the rod 17, and the holes are spaced apart differently from the spacing of the holes 23 in the bracket. In the structure shown there are three of the holes 26 in the lever-head, and the distance from center to center of said holes is one-third greater than the distance from center to center of the holes 23, or, for example, if said holes 23 are spaced 1½ inches apart, the holes 26 should be 2 inches apart. By this vernier-like relation of the two series of holes, in the bracket and lever, pairs of the holes may be brought into register, to receive the fulcrum-pin, by variations in the relation of the bracket and lever of only one-third the distance between the holes 23. Thus a much more accurate adjustment of the slack of the brakes may be made than is possible by the usual construction, wherein there is a single fulcrum-pin hole in the lever, as before noted. The advantages inherent in accurate slack-adjustment of brakes, whereby uni-

formity of piston-travel and braking-pressure may be attained, are well-known to those skilled in the art, and need not be here enlarged upon. Obviously, any desired 5 number of holes may be provided in the lever-head, the spacing of such holes being in such proportion to the holes in the bracket as to successively come into register with the latter by uniform variations in the relations 10 of the lever and bracket. In actual practice, however, the number of holes shown is sufficient to attain the desired result, and is preferable for the reason that the lever-head need not be very large.

15 In Figs. 4, 5 and 6 there is shown the application of my invention to brake-rigging of the type in which slack-adjustment is effected by variations in the relation of the cylinder-lever and the brake-piston-rod. In 20 this type of brake-rigging the piston-rod 19 carries at the end thereof a yoke 28 of which the intermediate portion comprises spaced parallel portions between which the end of the cylinder-lever extends, and with which it 25 is connected by a fulcrum-pin 29. The hand-brake-rod 20 is connected directly with the end-portion of the yoke, instead of being connected with an extended portion of the cylinder-lever as in the arrangement shown 30 in Fig. 1. In the parallel spaced plate-portions of the yoke 28 there are a plurality of holes 30 arranged in two longitudinal rows, the holes in each row being uniformly 35 spaced apart, and being in interspaced or staggered relation to the holes of the other row. The cylinder-lever 16' has a separate head 31 which fits slidably between the sides of the yoke, said head being formed with a 40 central recess or socket into which the end of the lever extends and with which it is fixedly connected by a bolt or rivet 32. In the head 31 are a plurality of holes 33 each adapted to receive the fulcrum-pin 29 when placed in register with one of the holes 30 45 of the yoke, for operatively connecting the yoke and lever in adjusted relations. The holes 33 are arranged, of course, at uniform radial distances from the center of the pin 34 which connects the lever with the rod 17, 50 and said holes are so spaced apart laterally of the lever as to have a vernier-like relation to the holes 30 of the yoke. Although the holes 30 are arranged in two longitudinal rows, the holes 33 in the lever-head may be 55 brought into register with the holes 30 of either row, by a slight longitudinal shifting of the lever, which is permitted by lateral swinging of the connecting-rod 17 and of the top-rod 14 which is connected with the 60 opposite end of the lever. Adjustments may thus be made in substantially the same manner as if the holes 30 were arranged in a single row and spaced apart at one-half the distances between the successive holes in each 65 of the two rows of the arrangement shown.

By the staggering of the holes, however, the distances from center to center of the holes, measured longitudinally and including the holes of both rows, may be shorter than would be practicable if all of the holes were 70 in a single row, and the amount of variation between the successive adjusted relations of the parts thus reduced.

Brake-adjusting means analogous to that herein described may be applied to brake-rigging of the types wherein the slack-adjustments are made at the truck-levers, and a specific application of such adjusting means to the dead-lever and dead-lever-guide is shown in my application for patent 80 thereon, filed May 12, 1924, Serial No. 712, 774.

It is noted that the term "equalizing-lever" is herein employed to designate broadly either the cylinder-lever, the floating-lever, or any lever employed in a system of brake-rigging to proportionally distribute the braking-force to a plurality of members, and wherein slack of the brakes may be adjusted by varying the relation of such lever to a part or member with which the lever has a fulcrumed or pivotal connection. The term "brake-lever" is similarly employed to designate any lever of a brake-rigging which may be varied in its relation 90 to a part or member with which it is pivotally connected or on which it is fulcrumed, to effect adjustments of slack or to compensate wear of the brakes.

Now, having described my invention, what 100 I claim and desire to secure by Letters Patent is:

1. Slack adjusting means for railway brakes, comprising, in combination, a brake-lever, a member with which said lever is 105 pivotally connected, said member having a series of fulcrum-pin holes uniformly spaced longitudinally thereof, said lever having a head adjoining said member, and said head having a plurality of fulcrum-pin holes 110 therein spaced differently from the holes in said member and adapted to register successively with the holes therein by variations in the relative position of the lever less than the distances between successive 115 holes of said series.

2. Slack-adjusting means for railway brake mechanism, comprising, in combination, an adjusting-member having a series of fulcrum-pin holes, a brake-lever having 120 a head adjoining said adjusting-member, said brake-lever-head having a plurality of fulcrum-pin holes arranged in vernier-like relation to the series of holes in the adjusting-member, whereby holes in the head may 125 register successively with holes in the adjusting-member when the lever is at adjusted positions intermediate those at which any one hole of the head is in register with any hole in the adjusting-member, and a 130

fulcrum-pin insertible through the registering holes to pivotally connect the lever and said adjusting-member.

3. In a railway brake-rigging, the combination of an equalizing-lever, a member associated with said lever in relations variable to compensate slack of the brake-rigging, said member having a uniformly spaced series of fulcrum-pin holes therein, said 10 equalizing-lever having a plurality of holes arranged in vernier-like relation to the series of holes in said member, whereby to register with successive holes of said series at adjusted relations of the parts varying by amounts less than the distances between adjacent holes of the series, and a fulcrum-pin insertible through the registering holes to pivotally connect the parts in said adjusted relations.

4. In a railway brake rigging, the combination of an equalizing-lever, a member associated with said lever in relations variable to compensate slack of the brake-rigging, said member having therein a series of fulcrum-pin holes uniformly spaced longitudinally and staggered transversely thereof, said equalizing-lever having a plurality of fulcrum-pin holes arranged to register separately but not simultaneously with holes of said series, whereby some of the holes 25 may be in register at adjusted relations of the parts varying by amounts less than the longitudinal distances between holes of said series, and a fulcrum-pin insertible through the registering holes to pivotally connect 30 the parts in said adjusted relations.

CHARLES O. ANDERSON.
